James E. Matthews,
INVENTOR
BY *Victor J. Evans*,
ATTORNEY

UNITED STATES PATENT OFFICE.

JAMES E. MATTHEWS, OF FARRELL, PENNSYLVANIA.

BASSINET CRADLE.

Application filed September 14, 1923. Serial No. 632,682.

To all whom it may concern:

Be it known that I, JAMES E. MATTHEWS, a citizen of the United States, residing at Farrell, in the county of Mercer and State 5 of Pennsylvania, have invented new and useful Improvements in Bassinet Cradles, of which the following is a specification.

My present invention has reference to improvements in basket cradles.

10 An object is to produce a basket cradle that is reinforced at the sides thereof to add to its stability, which is provided with means to permit of the swinging thereof either by hand or foot, and which is further provided with locking means to prevent the swinging of the cradle when the child is rolling, romping or sleeping therein.

20 A further object is to produce a basket cradle which is of a construction to permit of the infant sitting crosswise therein and which is provided with an automatic brace for the infant's feet to prevent the infant from sliding in or out of the basket.

25 With these and other objects in view which will appear as the nature of the invention is better understood, the improvement resides in the construction, combination and operative arrangement of parts, 30 such as is disclosed by the drawings which accompany and which form part of this application.

In the drawings:—

Figure 1 is a side elevation of a basket 35 cradle constructed in accordance with this invention.

Figure 2 is a top plan view thereof.

Figure 3 is an end view thereof.

40 Figure 4 is a sectional view approximately on the line 4—4 of Figure 3.

Figure 5 is a sectional view approximately on the line 5—5 of Figure 1.

Figure 6 is a sectional view approximately on the line 6—6 of Figure 1.

45 Figure 7 is a perspective view of the hook carrying straps.

Referring now to the drawings in detail, the numeral 1 designates the basket which is of the usual elliptical formation, but 50 which has its bottom of wood, as indicated by the numeral 2. The sides of the basket are reinforced at the center thereof by suitable sheets 3 of cardboard or like material, and the basket has at its ends substantially U-shaped handles 4 respectively.

55 Preferably the connecting element for

the arms of the U-shaped handles are of wood, or a wooden block may be arranged in the rounded inner portion of the said handles. In either event, the wooden portion of the handle is provided with a round opening 5. Each opening 5 receives therethrough the reduced rounded portion 6 of a cross sectionally rounded pin 7. Preferably the pins are of metal and embody sufficient strength to sustain the basket and the infant therein on the stand or frame which will now be described.

The stand has its ends A-shaped, that is the legs 8 at the ends of the stand are arranged at an inward angle with respect to each other and are connected at their meeting ends by a V-shaped block 9 and by a lower block or plate 10 which is slightly spaced from the block 9. At the extreme 70 upper portions the ends 8 of the stand are provided with heads 11 which may be ornamented. The pins 7 are designed to be received between the blocks 9 and 10. By reference to the drawings it will be seen 75 that the block 9 is arranged on the outer face of the legs 8 and that the block 10 is arranged on the inner face of the said legs. Thus the pins 7 will rest directly upon the lower blocks 10 and bear against the lower 80 edge of the upper blocks 9. In this manner the pins are effectively sustained on the frame, and likewise in this manner the basket is removably arranged between the end members of the frame or stand.

90 The A-shaped ends provided by the legs 8 of the stand are connected adjacent to their lower ends by transverse brace members 12 and to these members 12 there are secured the ends of the longitudinal lower 95 members 13 of the stand. The members 13 are centrally connected by a brace element 14. Other transverse brace members may be secured to the ends of the stand, one of said members, indicated for distinction by 100 the numeral 14', having its central portion concaved inwardly and rounded in cross section to provide a handle whereby the stand may be grasped and moved from place to place.

105 The leg members at the A-shaped ends of the stand are also connected by longitudinal bars 15 which are disposed only a slight distance below the bottom of the basket, and connected to these bars and to the sides of 110 the legs at the upper portions thereof there are angle brace bars 16.

On the under face of the wooden bottom of the crib there is centrally pivoted, as at 17, a bar or cleat 18. The cleat, when arranged longitudinally of the bottom is brought against a stop member 19, and when swung transversely of the bottom is also brought against a stop member 20. When in last mentioned position, the ends of the bar or cleat will contact with the bars 15 of the frame or stand so that the crib will be held from rocking movement.

The upper edge of the basket crib is ribbed or rolled in the usual manner and to the opposite sides of the reinforcements 15 there are secured to this rib or roll loops 21. One or both pairs of loops are designed to engage with hooks 22 on elements 23 secured to the ends of strap members 24. One of the strap members has its free end provided with a buckle or the like whereby the second strap member is adjustably secured thereto, and these straps are designed to prevent the infant in the crib from falling out of the same.

25 The ends of the frame or stand at the upper portions thereof have inwardly extending hooks 25, and to these hooks there is attached the looped ends of a heavy elastic cord or cable 26. The cord or cable 30 serves as a support for a mosquito netting and is elevated above the cradle a sufficient distance to prevent the infant therein pushing or kicking the same off of the device.

35 The bars or connecting elements 13 which provide the base of the stand, adjacent to their diagonally opposed ends are provided with reduced cross sectionally round portions 27. As the elements 13 are preferably of wood, the reduced portions 27 thereof 40 may be reinforced by metal bands. These reduced portions are designed to retain thereon, by means 28, a foot pedal 29. The

inner end of the foot pedal has attached thereto a light chain 30. The outer end of the chain is provided with a hook 31 and 45 this hook is designed to be arranged over the rolled or ribbed edge of the crib or cradle. When the bar or cleat 18 is arranged longitudinally of the crib or cradle, the pedal may be operated to rock the cradle by foot. The cradle is projected a suitable distance beyond the sides of the stand to permit of the same being readily rocked by hand. Also the stand is of such construction that free access may be obtained 55 to the infant in the cradle, and it is thought that the foregoing description, when taken in connection with the drawings will fully set forth the construction and advantages of the improvement to those skilled in the art to which this invention relates.

Having described the invention, I claim:—

The combination with a basket cradle, a frame from which the basket is hung and said frame including a pair of longitudinal bars, one at each side of the cradle and disposed in a horizontal plane directly therebelow the bottom of the basket, of a means 70 for locking the basket from swinging, comprising a bar centrally pivoted to the bottom of the basket, a stop element on said bottom of the basket with which the bar contacts when in longitudinal position, a 75 second stop element on the bottom of the basket for contact with the bar when the latter is swung transversely, and said bar when in last mentioned position designed to contact with the longitudinal bars of the 80 cradle supporting frame.

In testimony whereof I affix my signature.

JAMES E. MATTHEWS.
